UNITED STATES PATENT OFFICE.

GEORGES GAUTHIER, OF MARSEILLE, FRANCE.

APPARATUS FOR DISINFECTION AND THE EXTERMINATION OF VERMIN.

No. 908,853.

Specification of Letters Patent.

Patented Jan. 5, 1909.

Application filed September 21, 1906. Serial No. 335,637.

To all whom it may concern:

Be it known that I, GEORGES GAUTHIER, a citizen of the Republic of France, residing in Marseille, in said Republic, have invented 5 certain new and useful Improvements in Apparatus for Disinfection and the Extermination of Vermin, of which the following is a specification.

This invention aims to provide a portable 10 apparatus by means of which disinfecting and vermin-exterminating gases may be readily generated and supplied to rooms or apartments from the exterior of the building, whereby such rooms or apartments may be 15 disinfected or have the vermin therein exterminated, or said operations may take place successively. To this end, the apparatus is mounted on a vehicle which may be self-propelled, or otherwise, and comprises improved 20 means whereby the necessary gases may be readily generated and supplied to the place to be treated.

In the accompanying drawings, in which 25 similar reference characters indicate corresponding parts throughout the views, Figure 1 is a plan-view of the apparatus, Fig. 2 is a front-view, Figs. 3 and 4 are side-views taken on opposite sides, and Fig. 5 is a vertical section of the furnace in which the gases 30 are generated.

As shown in the drawings, the apparatus is mounted upon a platform provided with wheels and the necessary running gear. The 35 particular form of running gear is unessential, and the wheels are merely indicated by dotted lines in Figs. 3 and 4.

Mounted upon the platform of the vehicle is a metallic furnace A which is made in two superposed parts, the lower part R being provided 40 with burners r which are supplied with liquid fuel from a tank L in which said fuel is contained, and which is mounted upon the platform and connected with the burners by a suitable pipe, as shown. In the upper part 45 of the furnace there is provided a pan J which receives through a port P the fluids for generating the deodorizing gas. Mounted below said pan, within the furnace, is an alcohol-burner K, in the form of a pot, by 50 which said pan is heated and the fluids vaporized. The burner or pot K is supported on a suitable support k on a horizontal plate h beneath which the burners r are arranged.

The furnace A communicates at its upper 55 part, by means of a pipe, with a filtering-box C by which the generated gases are purified,

after which they are cooled by passing into a metallic tank B arranged on the platform adjacent the furnace. In the tank B, which is filled with water, there is placed a refrigerating-coil of any approved construction.

O denotes the water-pump.

D denotes an exhaust fan, which is connected with the tank B in such a way as to draw off the gases therefrom, said fan being 65 driven by a motor E arranged at the front of the platform and connected with the fan by a belt or other transmission mechanism. Said motor may in practice be used as the motor for driving the vehicle. The motor is 70 cooled by means of a cooling device F arranged on the platform between the motor E and the exhaust fan and communicating with the refrigerating-tank B. M denotes the ignition device for the motor. The fan 75 D is connected by means of a plurality of pipes H with the rooms to be treated, the gases being forced through the pipes and sucked back from the rooms into the furnace A by means of a pipe G entering the furnace 80 at its lower part and provided with nozzles, as shown, for connection with the return-pipes. I is the aspiration-pipe connected with the fan D whereby the gaseous mixtures from the rooms under treatment are 85 returned to the atmosphere when the process is ended.

When the apparatus is to be used for the extermination of vermin, there is placed on the horizontal plate h of the furnace A a mixture of sulfur and charcoal. The burners r in the part R of the furnace are then ignited, whereby a deadly gas is generated. The motor is then started and this sets in motion the fan D which sucks the gas from the furnace A into the filter, which cleanses the same, and from the filter the gas is sucked 90 into the refrigerating-tank B, which has a cooling action thereon. From said tank the gas is sucked through the fan D which forces 100 it through the pipes H into the rooms or apartments to be treated. The suction of the fan causes the air and gas in the rooms to be sucked back into the furnace through the pipes which are connected to the nozzles 105 of the pipe G connected with the lower part of the furnace. Thus the fan causes a continuous circulation of the gas to be produced. Instead of charcoal and sulfur, other substances may be used to generate the deadly 110 vermin-exterminating gas.

When using the apparatus for deodoriza-

tion or disinfection, the alcohol-burner K is filled with alcohol and the liquids to be vaporized are poured into the pan J by means of the port P. When the alcohol-burner is 5 ignited the disinfecting gas is generated and circulates in the manner above described.

Having thus described my invention, I claim as new and desire to secure by Letters Patent:

- 10 An apparatus for disinfection and the extermination of vermin, comprising a furnace having an interior horizontal plate on which substances forming a deadly gas may be burned, burners beneath said plate for heating such substances, a pan in the upper part 15

of the furnace to hold a liquid to be vaporized, a burner above the horizontal plate for heating said pan, an exhaust fan, and a connection between said fan and the upper part of said furnace whereby the disinfecting gas or the vermin-exterminating gas generated therein is forced into the rooms to be treated.

In testimony, that I claim the foregoing as my invention, I have signed my name, in 25 presence of two subscribing witnesses.

GEORGES GAUTHIER.
